UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

DEVICE FOR REGULATING BALANCE-WHEELS.

1,228,820.

Specification of Letters Patent.

Patented June 5, 1917.

Application filed December 26, 1916. Serial No. 138,945.

To all whom it may concern:

Be it known that I, WILSON E. PORTER, a citizen of the United States, residing at New Haven, in the county of New Haven and State of Connecticut, have invented a new and useful Improvement in Devices for Regulating Balance-Wheels; and I do hereby declare the following, when taken in connection with the accompanying drawings 10 and the characters of reference marked thereon, to be a full, clear, and exact description of the same, and which said drawings constitute part of this application, and represent, in—

15 Figure 1 a view in front elevation of a device embodying my invention, for regulating balance-wheels.

Fig. 2 a plan view thereof.

20 Fig. 3 a view in vertical section on the line 3—3 of Fig. 2 of the rocking balance-wheel carrier shown as detached, and on the double scale.

Fig. 4 a broken detail transverse sectional view, on the line 4—4 of Fig. 1.

25 Fig. 5 a detached broken detail plan view, showing the means employed for frictionally holding the end of the hair-spring to be adjusted.

30 My invention relates to an improved device for regulating the balance-wheels of marine-clock movements and of watch movements, the object being to produce, for the purpose described, a simple, accurate and compact device constructed with particular 35 reference to visualizing the oscillation of the master balance-wheel and the balance-wheel to be adjusted so as to enable the oscillation of the latter to be readily compared with the oscillation of the former.

40 With these ends in view, my invention consists in a device for regulating the balance-wheels of clocks and watches, the said device having certain details of construction 45 as will be hereinafter described and pointed out in the claims.

In carrying out my invention as herein shown, I employ a standard indicator 5 and a trial indicator 5', these two indicators being positioned to oscillate in close proximity 50 to each other so as to centralize, as it were, the comparison of their oscillations.

The standard indicator 5 is bent forward at a right angle from an arm or shank 6, staked upon an oscillating staff 7 having 55 pointed pivot ends which are journaled in

hardened cup-bearings 8 and 9. The said staff 7 also carries an inwardly extending arm 10 mounting a slotted plate 11, receiving the outer end of the hair-spring 12 of the master balance-wheel 13, the end of the 60 spring being secured in the slot in the plate 11 by means of a wedge 14.

The trial-indicator 5' is bent rearward at a right angle from an arm or shank 15 staked upon a staff 16 having pointed pivot 65 ends of which its pointed inner end bears in the bearing 9 before mentioned, while its pointed outer end bears in a cup-bearing 17 corresponding to the bearing 8. The said staff 16 mounts an inwardly extending arm 18 carrying a stud 19 formed with a notch 20 for the reception of the outer end of the hair-spring 21 of the balance-wheel 22 to be regulated, the said end of the spring 21 being frictionally held in the notch 20 by 70 means of a gripping-spring 23 coiled at its upper end to form a finger-piece 24 and having its opposite end coiled upon the staff 16 as at 25 to fasten it thereto.

Two stop-pins 26 located above and below 80 the arm 18 are provided for limiting the oscillation thereof, while stop-pins 27 (only one of which is shown) are correspondingly arranged above and below the arm 10 and limit the oscillation thereof, the object being 85 to limit the movement of the outer ends of the springs 12 and 21 as much as possible consistent with getting a sufficient movement of the indicators 4 and 5 for their comparison.

90 For mounting the master balance-wheel 13 and the balance wheel 22 to be regulated, I employ, as herein shown, a rocking balance-wheel carrier comprising three corresponding sector-shaped plates 28, 29 and 30 95 secured together and spaced apart by pillars 31 of any approved construction.

100 The master balance-wheel 13 is mounted upon a staff 32 pointed at its ends and oscillating in a screw cup-bearing 33 mounted in the rear plate 30 and in a double ended screw cup-bearing 34 mounted in the intermediate plate 29, while the balance-wheel 22 to be regulated is mounted upon a staff 35 pointed at its ends and oscillating in the forward end of the cup-bearing 34 aforesaid, and in a screw cup-bearing 36 mounted in the front plate 28, and having at its forward end a knurled button 37 by means of 105 which the bearing 36 is turned in and out so 110

as to provide for the convenient introduction and removal of the balance-wheels to be regulated, each balance-wheel to be regulated being organized with its hair-spring 21 and staff 35 and handle as a unit.

5 The rocking balance-wheel carrier above described, is mounted in front and rear frame-plates 38 and 39 secured together by pillars 40. For the purpose of rocking the 10 said carrier between these plates, I employ a stud 41 provided at its rear end with a threaded shank 42 entering the forward section of the two-part pillar 31, (Fig. 4) and at its forward end with a trunnion 43 15 passing forward through the frame-plate 38. The projecting forward end of the trunnion 43 mounts a pinion 44 meshed into by a segmental rack 45 turning on a stud 46 in the said plate 38 and furnished with an outwardly extending hand-lever 47. The rear member of the two-part pillar 31 is formed 20 with a bore 48 for the reception of a trunnion 49 formed upon a stud 50 fixed in the rear frame-plate 39. A helical spring 51 secured to the right hand pillar 31 of the 25 rocking carrier and to the lower right hand pillar 40 of the main frame formed by the plates 38 and 39, provides for returning the carrier to its upright position in which it 30 rests against a suitable buffer 52 in which position the carrier is normally maintained by the tension of its said spring.

In the use of my invention, the hair-spring 12 of the master balance-wheel 13 is 35 nicely adjusted so that the said wheel will have the correct number of oscillations per second for a clock or watch of the series in which the balance-wheels to be regulated are to be used.

40 Preparatory to the introduction into the device of a stock balance-wheel representing the balance-wheel units to be regulated, the screw cup-bearing 36 is unscrewed by its knurled button 37 so as to widen the gap between its cupped inner end and the cupped forward end of the double-ended screw cup-bearing 34. The rear pivot of the staff 35 of the balance-wheel unit to be adjusted, is now inserted into the cupped forward end 45 of the double-ended cup-bearing 34 after 50 which the screw 36 is turned home so as to provide a bearing for the forward pivot of the staff 35. The free end of the hair-spring 21 of the stock balance-wheel unit is then 55 inserted into the notch 20 of the stud 19 and frictionally held in place in the said notch by the pressure of the gripping-spring 23. The balance-wheels 13 and 22 are now 60 brought to absolute rest after which the hand-lever 47 is smartly depressed, with the effect of rocking the rocking-carrier from right to left, into the position shown by dotted lines in Fig. 1. Pressure being removed from the lever 47, the helical spring 65 51 immediately restores the carrier to its

upright position. The described rocking of the carrier, sets the two balance-wheels oscillating simultaneously, but this continues only for an instant, after which the balance-wheel 22 to be regulated will begin to oscillate slower or faster than the master balance-wheel 13 according to the initial positioning of the outer coil of its hair-spring 21 in the notch 20 of the stud 19. The workman now moves the outer coil of the hair-spring 21 through the notch 20 in one direction or the other until the oscillation of the balance-wheel 22 synchronizes perfectly with the oscillation of the master balance-wheel 13 as shown by the synchronous 70 movement of the indicators 5 and 5'. The workman now brings the two balance-wheels to absolute rest, after which he will again rock the carrier so as to again effect the simultaneous oscillation of the balance-wheels the comparative oscillations of which will be immediately visualized in the relative movement of the indicators. He now again adjusts the hair-spring 21 in the notch 20 until the indicators 5 and 5' move 80 synchronously. This process is repeated until the two balance-wheels are shown by the indicators to oscillate synchronously for a predetermined number of beats, say, 20 by 85 count. When this occurs, the end of the outer coil of the hair-spring 21 is bent over as shown by broken lines in Fig. 3, upon the upper edge of the stud 19 to mark the point 90 at which the coil must be held in the clock or watch movement of the series to which it belongs. The screw cup-bearing 36 is then unscrewed by its knurled button 37, permitting the now regulated balance-wheel 95 unit to be removed and replaced by another balance-wheel unit, and so on.

105 I claim:

1. In a device for regulating balance-wheels, the combination with a rocking carrier mounting a master balance-wheel and the balance-wheel to be adjusted, of indicators mounted in the said carrier, respectively connected with the outer ends of the hair springs of the said balance-wheels and arranged in conjunction with each other for the comparison of their relative oscillatory 110 movement.

2. In a device for regulating balance-wheels, the combination with a rocking carrier mounting a master balance-wheel and the balance-wheel to be adjusted, of indicator staffs mounted in the carrier for oscillation therein, indicators carried by the respective shafts and located in opposition to each other, and means connecting the said shafts with the outer ends of the hair-springs 115 of the respective balance-wheels, whereby the relative oscillation of the said wheels is visualized for comparison.

3. In a device for regulating balance-wheels, the combination with a rocking-car- 120

- rier mounting a master balance-wheel and the balance-wheel to be regulated, oscillatory indicator-staffs mounted in the said carrier, indicators carried by the respective 5 staffs and arranged in opposition for the comparison of their movement, and means for connecting the outer ends of the hair-springs of the said wheels with the said shafts, the hair-spring of the balance-wheel 10 to be regulated being adjustably connected with its indicator staff.
4. In a device for regulating balance-wheels, the combination with a rocking carrier mounting a master balance-wheel and the balance-wheel to be regulated, oscillatory indicator-staffs mounted in the said carrier, indicators carried by the said staffs and arranged in opposition for the convenient comparison of their movement, connection 15 between the outer end of the hair-spring of the master balance-wheel with one of the said staffs, and connection between the hair-spring of the balance wheel to be 20
- adjusted with the other staff, the latter connection including a notched stud receiving 25 the end of the hair-spring of the said balance-wheel, and a gripping-spring for holding the hair-spring in position in the said notch.
5. In a device for regulating balance-wheels, the combination with a rocking-carrier mounting the master balance-wheel and the balance-wheel to be adjusted, of indicators respectively connected with and operated by the hair-springs of the said 30 balance-wheels for the comparison of their relative movement, the said indicators being bent toward each other in the same plane so as to centralize the comparison.

In testimony whereof, I have signed this 40 specification in the presence of two subscribing witnesses.

WILSON E. PORTER.
